UNITED STATES PATENT OFFICE.

LAWRENCE C. LUCAS, OF CANTON, OHIO.

HEATER.

1,367,064.

Specification of Letters Patent.

Patented Feb. 1, 1921.

Application filed June 8, 1918. Serial No. 239,072.

To all whom it may concern:

Be it known that I, LAWRENCE C. LUCAS, a citizen of the United States, residing at Canton, in the county of Stark and State of Ohio, have invented new and useful Improvements in Heaters, of which the following is a specification.

This invention relates to new and useful improvements in heaters and the principal object of the invention is to provide means for securing a maximum amount of heat from a minimum amount of fuel.

Another object of the invention is to provide a device of this character which is simple and durable in construction, reliable and efficient in operation and one which can be manufactured and placed upon the market at a minimum cost.

The invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a front view of the device arranged as a heater.

Fig. 2 is a transverse section.

Fig. 3 is an end view.

Fig. 4 is a perspective view of part of the heater.

Fig. 5 is a transverse vertical sectional view of a modification.

Fig. 6 is a longitudinal sectional view through such modification.

Fig. 7 is a horizontal section through another modification.

Fig. 8 is a transverse section through such modification.

Fig. 9 is a perspective view of the burner.

In these views 1 represents the casing forming the exterior of the device. The top of the casing is connected with the distributing pipes 2 leading to the rooms or places to be heated. 3 is the air inlet connected with the bottom of the casing and this inlet may draw the air in from the exterior of the building or from one of the lower rooms thereof. If desired this inlet may be connected with air forcing means for producing artificial draft through the

system. I prefer to have the inlet connect with a passage-way 4 which extends under the entire floor of the casing between said floor and the bottom of the casing and this passage-way communicates with said casing through a slot 5 in the floor of the casing adjacent the opposite wall of said casing so that the incoming air will pass under the floor of the casing and be directed upwardly along the rear wall thereof. The inlet 3 forms a continuation of the passage-way. 6 represents the heater made in the form of a rectangular casing and located in the casing 1 adjacent said slot.

As shown the heater is of substantially the same length as the casing so as to extend from end to end thereof. This is of considerably less width than the casing and an L-shaped baffle plate 7 has one limb located above the top of the heater and its other limb extending downwardly parallel with said heater with its end spaced a short distance from the bottom of the casing. It will be seen that this baffle plate divides the casing into an upper chamber and a lower chamber so that the incoming air will pass upwardly between the heater and the rear wall of the casing, over the top of the heater and down between the heater and the vertical limb of the baffle plate, through the space between the end of said limb and the bottom of the casing into the upper chamber and from this upper chamber the heated air will pass into the distributing pipes. Thus the air is distributed in a thin layer around the heater so that it will quickly absorb the heat from the heater and said air will also be heated in the upper chamber as this chamber will be heated by said heater. The products of combustion from said heater are carried off by the pipe 8 which may lead to a chimney.

The burner shown in Figs. 4 and 9 is made of greater length than the heater and the casing so that it will project beyond the end of the casing, to receive the conducting pipe leading from a suitable source of fuel supply. As shown in said figures the burner consists of the tube 12 secured to the semi-circular air duct 13. This air duct also projects beyond the end of the casing so that the air may flow into its open end. The sides of this duct are provided with the holes 14 so that the air may pass from said duct into the heater and thus aid in the combustion of the gases. The tube 12 is divided

in half by a horizontal partition 15 which is slotted so that the mixture of gas and air introduced into the compartment below the partition will flow through said slots into 5 the upper compartment and the mixture will flow from this compartment through the perforations 16 formed in the upper part of the tube. It will be understood that the ends of the upper compartment are closed. 10 In the modification shown in Figs. 5 and 6 a pair of heaters 6' is used and these heaters are separated by a baffle plate 7* extending downwardly from the horizontal limb of the L-shaped baffle 7'. These heaters 15 are held in position by means of supporting bars 17 connected with the ends of the casing. Angle bars 7° form tracks for the rollers 10. In this modification the outlet pipe 8' is forked with its forked ends 20 engaging said heaters.

In this modification the incoming air will pass around the first heater through the space between the baffle 7* and the bottom of the casing, around the second heater and 25 through the space below the vertical limb of the baffle 7' into the upper chamber as before described.

In the modification shown in Figs. 7 and 8 the baffle plates 18 extend from the top to 30 the bottom of the casing, and each plate has one of its ends spaced from the end of the casing so that the incoming air will be caused to flow in a horizontal path through said casing. It will, of course, be understood 35 that the inlets and outlets are changed accordingly. In this case as in the modification just described the heaters themselves act as baffle plates to change the direction of travel of the air currents.

40 It will be seen that the products of combustion are so retarded in their passage through the heater that they will give up most of their heat to the walls of said heater and the surrounding air. The incoming air 45 is also retarded in its passage around the heater so that said air will be intensely heated in its slow movement around said heater and due to the fact that the air is dis-

tributed in a thin layer around the heater 50 all parts of it will be subjected to the heating action. In this way the maximum degree of heat is secured from the minimum amount of fuel consumed.

It will, of course, be understood that the device may be made of any desired size. 55 Said device may be made to be located in the basement of a building, as an ordinary furnace, or it may be small enough to be used for heating a single room.

It is thought from the foregoing description 60 that the advantages and novel features of my invention will be readily apparent.

I desire it to be understood that I may make such changes in the construction and in the combination and arrangement of the 65 several parts, provided that such changes fall within the scope of the appended claims.

What I claim is:—

1. A device of the class described comprising 70 a main casing having air inlet and outlet ports, a closed heater casing in said main casing acting as a baffle for the air current, a chimney pipe connected with the heater casing, a burner in said heater casing 75 and a baffle plate in said main casing cooperating with the heater casing for giving the air current a zig-zag path.

2. A device of the class described comprising 80 a main casing having a slot in its bottom along one wall thereof, an air conduit under said bottom and extending from end to end of the casing and leading to said slot, a closed heater casing in the first mentioned casing extending from end to end of 85 the same and having one side in alignment with the inner wall of the slot so as to force the air passing through the slot upwardly between itself and one wall of the main casing, a burner in said heater casing, a chimney pipe connected with said heater casing 90 and an L-shaped baffle plate for directing the air across the top and along the inner side of the said heater casing.

In testimony whereof I affix my signature. 95
LAWRENCE C. LUCAS.
